UNITED STATES PATENT OFFICE.

ATANAS P. DULGEROFF, OF PADUCAH, KENTUCKY.

COMBINED KITCHEN-TABLE AND IRONING-BOARD.

1,330,851.

Specification of Letters Patent.

Patented Feb. 17, 1920.

Application filed May 31, 1919. Serial No. 301,053.

To all whom it may concern:

Be it known that I, ATANAS P. DULGEROFF, a citizen of the United States, residing at Paducah, in the county of McCracken and 5 State of Kentucky, have invented certain new and useful Improvements in Combined Kitchen-Tables and Ironing-Boards, of which the following is a specification, reference being had to the accompanying 10 drawings.

This invention relates to convertible furniture, and particularly to kitchen tables which are adapted to be converted into ironing tables, that is which are provided with 15 an ironing board adapted to be turned to or from an operative position.

The general object of this invention is to provide an article of furniture of the class described so constructed that the ironing 20 board under ordinary circumstances forms part of the top of the table, the ironing board, however, being shiftable to a projected and operative position as an ironing board, there being means for filling the space 25 in the top of the table formerly occupied by the ironing board.

A further object is to provide an ironing board which forms a section of the top of the kitchen table and which is pivoted thereto 30 for movement from its position as part of the top to a projected position, and provide a filling board hingedly connected to the ironing board proper which, when the ironing board is projected into its operative position as an ironing board, is lifted into its place to fill the space in the top of the table 35 formerly occupied by the ironing board.

A further object is to provide a sleeve 40 board detachably mounted upon the ironing board, and provide means for supporting the sleeve board when not in use, and a bracket mounted on the ironing board to support the sleeve board in operative position, the filling board being formed with a 45 slot to receive said bracket when the ironing board and filling board are turned into parallel position.

A further object is to provide a convertible article of the character described which 50 is very simple in construction, effective in use, and which will not have the objectionable features incident to other constructions of this character.

My invention is illustrated in the accompanying drawings, wherein:—

Figure 1 is a top plan view of a combined

ironing board and kitchen table constructed in accordance with my invention and showing the parts in their folded position;

Fig. 2 is a front elevation, partly in section, of the table;

Fig. 3 is an end elevation of the table;

Fig. 4 is a sectional view of the leaf 17 and the bracket for supporting the sleeve board;

Fig. 5 is a top plan view showing the ironing board in its operative position; and

Fig. 6 is a side elevation of the table with the parts in the position shown in Fig. 5.

Referring to these drawings, it will be 70 seen that the table is constructed in the usual manner of kitchen tables, and comprises a table top 10, the legs 11, the longitudinally extending supporting beams 12, and the transversely extending end supporting beams 75 13, and medial supporting beams 14. These beams 12, 13 and 14 are cut away, as will be later described.

The table top 10 is formed of two spaced sections having their confronting edges convergent in one direction so as to leave, longitudinally of the table, an open space 15 which is to be filled normally by the ironing board. One end beam 13 is cut away, as at 16. The ironing board is designated 17 and 80 85 has a total length equal to the total length of the table and a width and shape the same as the width and shape of the opening 15, that is it is broader at one end than at the other. Adjacent the butt or larger end of 90 the ironing board, it is pivoted to the two lateral sections of the table top 10 by means of dowel pins 18. These dowel pins are disposed the same distance from the edge of the table top 10 as they are from the butt end of 95 the board 17. As a consequence, when this board 17 is rotated to the position shown in Fig. 1, to fill the space 15 and form part of the table top, the butt end of the ironing board will be coincident with the end edge 100 of the table top. Hinged to the butt end of the board 17 is a filling board 19. The hinges are designated 20. These hinges are so formed as to permit the board 17 to be laid over upon and approximately parallel 105 with the board 19 by a movement in one direction, but when the board 17 is in its projected position, as illustrated in Fig. 5, the board 19 will be in a horizontal position and cannot be depressed below this horizontal 110 position.

The transverse beams 14 are cut away to

accommodate the board 19. Normally, as before stated, the ironing board 17 is disposed so as to fill the opening 15 and with its upper face flush with the upper face of the 5 table. Under these circumstances the filling board 19 will be drawn longitudinally so that its butt edge is coincident with the butt edge of the ironing board 17, but its narrow edge will be inward of the adjacent edge of 10 the table top 10, this filling board under these circumstances resting upon the transverse frame beams 14. When the ironing board 17 is moved to its projected position, the filling board 19 will be shifted longitudinally of the table and then raised to a 15 position where it is flush with the table top. The narrow end of the filling board 19 and the narrow end of the ironing board 17 are both transversely grooved, as at 21, for engagement by a pivoted latch 22, one end of 20 which is pivoted in a groove in one section of the table top 10, the free end being received within a groove 23 formed in the opposite section. Thus, in both positions the 25 boards will be fully supported. The ironing board is formed with a metal socket 24 for the reception of a leg or standard 25 which may be engaged in the socket in any suitable manner, but should be readily disengaged therefrom. The end beams 13 and 14 may be provided with longitudinally 30 extending registering openings for the reception of this leg or with a circular housing 26 to receive this leg when not in use.

35 In order to provide for the support of a sleeve board upon the ironing board, I mount upon the ironing board a bracket or support 27 having downwardly extending legs at its forward and rear ends, these legs being 40 flanged and attached to screws at the top of the ironing board, the upper face of the bracket being formed with a longitudinally extending slot 28 and with a perforation for the reception of a pin 29 extending downward from the sleeve board 30. The sleeve board 30, rearward of the pin 29, is provided with a screw stud 31 having a head which is adapted to pass through the slot 28, this slot 45 being open-ended, and thus the sleeve board may be lowered until the pin 29 engages in the perforation in the bracket. Thus the sleeve board will be supported in a horizontal position, as illustrated in Fig. 6. When it is desired to attach the sleeve board, the 50 sleeve board is raised to disengage the pin 29 and then shifted rearward until the headed stud 31 disengages from the slot 28. The front beam 12 of the ironing table is formed to provide an opening and guides for the 55 reception of the drawer 32, and also provided with a slide opening 33 to receive the sleeve board. The filling board 19 is formed with a slot 34 to accommodate the bracket 27 when the ironing board 17 is turned over 60 into parallel relation to the filling board.

It will be seen that under ordinary circumstances the ironing board 17 is turned over upon the filling board 19 and entirely fills the opening 15 so that a kitchen table is provided, the top of which is practically unbroken and practically fulfills all the conditions of a kitchen table, the latch 22 under these circumstances latching the ironing board in place. When it is desired to use the ironing board, the ironing board is 70 turned over to its operative position, the filling board lifts into the space 15 and is locked by the latch 22 and the leg 25 is put in place to support the ironing board. The sleeve board may, of course, be used whenever desired. It will be seen that the kitchen table 75 conforms in construction and shape to the ordinary kitchen table and may be made of the same material and in the same manner. It will be seen, furthermore, that the ironing board is fully housed within the kitchen 80 table when not in use, and that that surface of the ironing board which is used for ironing, and which may be padded, is the surface which is downward when the ironing board 85 is in place within the opening 15 and fulfills its function as part of the table top.

While I have illustrated a form of the invention which I believe to be thoroughly effective, it will be obvious that many 90 changes might be made in the details of construction and arrangement of parts without departing from the spirit of the invention.

I claim:—

1. A table of the character described having a top formed with a longitudinal opening extending from one end toward the other end of the top, an ironing board pivotally supported at one end of the table top and disposed within the longitudinal opening 100 and fitting the same and shiftable from a position filling said opening and wherein it is flush with the table top and forms part thereof, to an outwardly projected position flush with the table top, and a filling board 105 operatively connected to the ironing board to shift into the space occupied by the ironing board and form part of the table top when the ironing board is shifted to its projecting position.

2. A table of the character described having a top formed with a longitudinal opening extending from and opening upon the end of the top, an ironing board pivotally connected at one end to one end of the table 110 top and disposed within said longitudinal opening and shiftable from a position filling said opening and wherein it is flush with the table top and forms part thereof, to an outwardly projected position flush with the 115 table top, and a filling board hinged to the butt end of the ironing board so that the ironing board may be turned over into parallel relation to the filling board, and when the ironing board is turned outward to its 120

125

130

projected position the filling board and the ironing board will be disposed in the same plane with each other and with the table top.

3. A table of the character described having a top formed with a longitudinal opening extending from end to end of the top, an ironing board pivotally supported at one end of the table top and shiftable from a position filling said opening, and where it is flush with the table top and forms part thereof, to an outwardly projected position, a filling board hinged to the butt end of the ironing board so that the ironing board may be turned over into parallel relation to the filling board, and when the ironing board is turned outward to its projected position the filling board and the ironing board will be disposed in the same plane with each other and with the table top, a sleeve board supporting bracket mounted on the butt end of the ironing board, the filling board being formed with a slot to receive said bracket when the filling and ironing boards are disposed in parallel relation, and the sleeve board detachably engageable with said bracket.

4. A table of the character described having a top formed with a longitudinal opening extending from end to end of the top, an ironing board pivotally supported at one end of the table top and shiftable from a position filling said opening, and wherein it is flush with the table top and forms part thereof, to an outwardly projected position, a filling board hinged to the butt end of the ironing board so that the ironing board may be turned over into parallel relation to the filling board, and when the ironing board is turned outward to its projected position the filling board and the ironing board will be disposed in the same plane with each other and with the table top, and a latch disposed at one end of the table opposite that end in which the ironing board is pivotally supported, said latch being engageable with the end of the ironing board when the latter is turned into a position alined with the table top to hold the ironing board in such position but being engageable with the filling board when the ironing board is projected.

5. A table of the character described having legs, a supporting frame and a table top formed in two laterally spaced sections to define an opening extending longitudinally of the table for its entire length, an ironing board having a length equal to the length of the table top and pivotally supported at its butt end between the sections of the table top so that it may be rotated from a position where it forms part of the table top to a projected position, and in both positions lie flush with the table top, a table leg for supporting the ironing board in a projected

position, a filling board, hinges disposed in the normally under face of the ironing board and on the upper face of the filling board, the filling board being supported for longitudinal shifting movement upon the frame of the table whereby when the ironing board is turned over flush with the table top, the filling board will be retracted longitudinally beneath the table top and will lie beneath the ironing board, whereby when the ironing board is turned over to its projecting position, the filling board will fill the space formerly occupied by the ironing board, the corresponding ends of the ironing board and filling board being transversely grooved, and a latch mounted on the table top at one end thereof and adapted to engage in either of said grooves.

6. A table of the character described having legs, a supporting frame and a table top formed in two laterally spaced sections to define an opening extending longitudinally of the table for its entire length, an ironing board having a length equal to the length of the table top and pivotally supported at its butt end between the sections of the table top so that it may be rotated from a position where it forms part of the table top to a projected position, and in both positions lie flush with the table top, a filling board, hinges disposed in the normally under face of the ironing board and on the upper face of the filling board, the filling board being supported for longitudinal shifting movement upon the frame of the table whereby when the ironing board is turned over flush with the table top, the filling board will be retracted longitudinally beneath the table top and will lie beneath the ironing board, whereby when the ironing board is turned over to its projecting position, the filling board will fill the space formerly occupied by the ironing board, the corresponding ends of the ironing board and filling board being transversely grooved, a latch mounted on the table top at one end thereof and adapted to engage in either of said grooves, a bracket mounted upon the butt end of the ironing board, a sleeve board detachably mounted on the bracket, the filling board being formed with a slot extending from its butt end to receive the bracket when the ironing board and filling board are turned to a parallel position, a leg for the ironing board detachable therefrom, and means formed in the frame of the table to receive and support the sleeve board and leg when not in use.

In testimony whereof I hereunto affix my signature in the presence of two witnesses.

ATANAS P. DULGEROFF.
